(57) **CLAIM**

We claim the ornamental design for a modular shelving assembly, as shown and described.

DESCRIPTION

FIG. 1 is a front perspective view of a modular shelving assembly in accordance with a first embodiment of the present invention.

FIG. 2 is a front view of the modular shelving assembly of FIG. 1.

FIG. 3 is a rear view of the modular shelving assembly of FIG. 1.

FIG. 4 is a left side view of the modular shelving assembly of FIG. 1.

FIG. 5 is a right side view of the modular shelving assembly of FIG. 1.

FIG. 6 is a top view of the modular shelving assembly of FIG. 1.

FIG. 7 is a bottom view of the modular shelving assembly of FIG. 1.

FIG. 8 is a front perspective view of a modular shelving assembly in accordance with a second embodiment of the present invention.

FIG. 9 is a front view of the modular shelving assembly of FIG. 8.

FIG. 10 is a rear view of the modular shelving assembly of FIG. 8.

FIG. 11 is a left side view of the modular shelving assembly of FIG. 8.

FIG. 12 is a right side view of the modular shelving assembly of FIG. 8.

FIG. 13 is a top view of the modular shelving assembly of FIG. 8.

FIG. 14 is a bottom view of the modular shelving assembly of FIG. 8.

FIG. 15 is a front perspective view of a modular shelving assembly in accordance with a third embodiment of the present invention.

FIG. 16 is a front view of the modular shelving assembly of FIG. 15.

FIG. 17 is a rear view of the modular shelving assembly of FIG. 15.

FIG. 18 is a left side view of the modular shelving assembly of FIG. 15.

FIG. 19 is a right side view of the modular shelving assembly of FIG. 15.

FIG. 20 is a top view of the modular shelving assembly of FIG. 15.

FIG. 21 is a bottom view of the modular shelving assembly of FIG. 15.

FIG. 22 is a front perspective view of a modular shelving assembly in accordance with a fourth embodiment of the present invention.

FIG. 23 is a front view of the modular shelving assembly of FIG. 22.

FIG. 24 is a rear view of the modular shelving assembly of FIG. 22.

FIG. 25 is a left side view of the modular shelving assembly of FIG. 22.

FIG. 26 is a right side view of the modular shelving assembly of FIG. 22.

FIG. 27 is a top view of the modular shelving assembly of FIG. 22.

FIG. 28 is a bottom view of the modular shelving assembly of FIG. 22.

FIG. 29 is a front perspective view of a modular shelving assembly in accordance with a fifth embodiment of the present invention.

FIG. 30 is a front view of the modular shelving assembly of FIG. 29.

FIG. 31 is a rear view of the modular shelving assembly of FIG. 29.

FIG. 32 is a left side view of the modular shelving assembly of FIG. 29.

FIG. 33 is a right side view of the modular shelving assembly of FIG. 29.

FIG. 34 is a top view of the modular shelving assembly of FIG. 29.

FIG. 35 is a bottom view of the modular shelving assembly of FIG. 29.

FIG. 36 is a front perspective view of a modular shelving assembly in accordance with a sixth embodiment of the present invention.

FIG. 37 is a front view of the modular shelving assembly of FIG. 36.

FIG. 38 is a rear view of the modular shelving assembly of FIG. 36.

FIG. 39 is a left side view of the modular shelving assembly of FIG. 36.

FIG. 40 is a right side view of the modular shelving assembly of FIG. 36.

FIG. 41 is a top view of the modular shelving assembly of FIG. 36.

FIG. 42 is a bottom view of the modular shelving assembly of FIG. 36.

FIG. 43 is a front perspective view of a modular shelving assembly in accordance with a seventh embodiment of the present invention.

FIG. 44 is a front view of the modular shelving assembly of FIG. 43.

FIG. 45 is a rear view of the modular shelving assembly of FIG. 43.

FIG. 46 is a left side view of the modular shelving assembly of FIG. 43.

FIG. 47 is a right side view of the modular shelving assembly of FIG. 43.

FIG. 48 is a top view of the modular shelving assembly of FIG. 43.

FIG. 49 is a bottom view of the modular shelving assembly of FIG. 43.

FIG. 50 is a front perspective view of a modular shelving assembly in accordance with an eighth embodiment of the present invention.

FIG. 51 is a front view of the modular shelving assembly of FIG. 50.

FIG. 52 is a rear view of the modular shelving assembly of FIG. 50.

FIG. 53 is a left side view of the modular shelving assembly of FIG. 50.

FIG. 54 is a right side view of the modular shelving assembly of FIG. 50.

FIG. 55 is a top view of the modular shelving assembly of FIG. 50.

FIG. 56 is a bottom view of the modular shelving assembly of FIG. 50.

FIG. 57 is a front perspective view of a modular shelving assembly in accordance with a ninth embodiment of the present invention.

FIG. 58 is a front view of the modular shelving assembly of FIG. 57.

FIG. 59 is a rear view of the modular shelving assembly of FIG. 57.

FIG. 60 is a left side view of the modular shelving assembly of FIG. 57.

FIG. 61 is a right side view of the modular shelving assembly of FIG. 57.

FIG. 62 is a top view of the modular shelving assembly of FIG. 57; and,

FIG. 63 is a bottom view of the modular shelving assembly of FIG. 57.

The portions of the modular shelving assembly shown in broken lines are included for the purpose of illustrating environment and form no part of the claimed design. The portions of the modular shelving system shown in broken lines having

unequal length segments illustrate the boundary of the claimed design and form no part of the claimed design.
